E. G. Siggars.

ATTORNEY

UNITED STATES PATENT OFFICE.

GEORGE COOK, OF BUFFALO, NEW YORK.

STEAM BOILER.

Application filed June 24, 1918. Serial No. 241,591.

To all whom it may concern:

Be it known that I, GEORGE COOK, a citizen of the United States, residing at Buffalo, in the county of Erie and State of New York, have invented a new and useful Steam Boiler, of which the following is a specification.

This invention has reference to steam boilers, and its object is to provide a boiler so constructed and reinforced that it may be made of lighter material than customary for a desired degree of pressure and may provide a greater heating surface than is usually provided in boilers of the type to which the invention relates.

In accordance with the invention the boiler comprises an inner and an outer shell spaced apart and strengthened by braces with the braces constituting the support for the inner shell, said boiler having a fire box at one end with water legs enclosing it and at or near the other end provided with a steam dome through which there is passed a corrugated smoke flue.

The inner shell of the boiler is traversed by water tubes carried at the ends by heads which may be removed from the shell, or any one or more of the water tubes may be removed, the outer shell having removable head plates whereby the entire face of either end of the shell carrying the water tubes may be reached. To further brace the structure, the water tubes, especially in short boilers, may be traversed by rods, in turn

traversing the heads and secured exterior thereto, or short bolts may connect the end plates of the inner shell and the removable heads of the outer shell.

The invention will be best understood from a consideration of the following detailed description taken in connection with the accompanying drawings forming part of this specification, with the understanding, however, that the invention is not confined to any strict conformity with the showing of the drawings but may be changed and modified so long as such changes and modifications mark no material departure from the salient features of the invention as expressed in the appended claim.

In the drawings:

Figure 1 is a longitudinal vertical section of a boiler embodying the invention.

Figure 2 is an elevation of the fire box end of the boiler.

Figure 3 is a cross section of the boiler with distant parts omitted.

Figure 4 is a section on the line 4—4 of Figure 2.

Figure 5 is a detail sectional view on a larger scale than the other figures, showing a form of stay bolt.

Figure 6 is a view similar to Figure 5, but showing another form of stay bolt.

Referring to the drawings, there is shown a boiler having two shells 1 and 2 respectively, the shell 2 being entirely enclosed in the shell 1. Ordinarily the shell 1 is circular in cross section, and the shell 2 has its top or crown portion more or less flattened, the shell 2 being otherwise circular in cross section. The two shells are held in approximately concentric spaced relation by stay bolts 3, 4 respectively, certain of the bolts, indicated at 3^a, being hollow and closed at the outer ends by screw plugs 3^b, whereby on the removal of a plug, a pipe may be screwed into the hollow stay bolt 3^a and compressed air or steam may be forced into the shell 2 for cleaning purposes, as will hereinafter appear. At suitable points in the bottom portion of the shell 1 are man-hole plates 6 and clamps 7 which may be constructed in accordance with the usual practice, these manholes giving access to the space between the shells to remove deposits of mud and the like, such space, when the boiler is in operation, being filled with water.

The shell 2 is provided with end plates 8 carrying a series of water tubes 9. The end plates 8 are bored or punched out as customary and the tubes 9 may be upset in the holes thus provided. The end plates are secured to the corresponding ends of the shell 2 by rivets 10 or in any other appropriate manner.

Fast to the ends of the shell 1 are end plates 11, each with an opening 12 therethrough of sufficient size to permit the entire shell 2 to be introduced or removed through it. Each opening 12 is normally closed by a head 13 held to the end plate 11 by bolts 14 or otherwise and between each plate 11 and head 13 there is introduced a gasket 15 to avoid leakage. The end plates 11 are strengthened by braces 15^a extending to the shell 1 and riveted or otherwise secured thereto.

When installed, the boiler is so supported

as to slant from one end toward the other. At the higher end the boiler is mounted upon a support 16 and at the lower end is mounted upon water legs 17 joined together to enclose a fire chamber 18, the water legs communicating with the space between the two boiler shells 1 and 2. The fire chamber is shown as provided with a grate 19 without any attempt to illustrate any particular form of grate. The fire chamber is also provided with a door 20 which may follow the customary practice and so needs no description further than to state that while the door is shown at the front of the fire chamber it may equally as well be placed at one side thereof.

The outer shell of the boiler is substantially cylindrical, while the inner shell is flattened at the crown and throughout its length so that a greater water space is provided between the crowns of the inner and outer shells. The inner shell is in communication with the fire chamber, while the outer shell is in communication with the steam dome, the shells being tilted upwardly and away from the fire chamber in such a manner that the greater volume of water in the boiler will be close to the fire chamber, thereby providing a greater steam space in the outer shell near the steam dome.

Extending through each head 13 and through certain ones of the water tubes 9 are rods 21, the water tubes being of sufficient internal diameter to permit the passage of the rods and leave ample space about them for the flow of water. Surrounding each rod 21, where passing through a head 13, is a screw bushing 22 screwed into the head 13 and traversed by the rod 21, which latter is there threaded for the reception of a nut 23. The bushing 22 is large at its outer end to form a seat 24 for the nut and the exterior of the bushing at its outer end is screw threaded to receive a cap 25. In this manner the rods 21 are readily accessible at any time it is desired to reach them, while the caps 25 form closures which may readily be made non-leakable.

The rods 21, which serve to hold the heads 13 from bulging, may be replaced by bolts 26, as shown in Figure 5, these bolts being carried at the outer ends by bushings 22 provided with caps 25 similarly to the showing of Figure 6. The bolts are made only long enough to traverse the space between the head 8 and plate 13 and seat in a bushing 22, each bolt having a head 27 interior to the plate 8.

Rising from the shell 1 at the end remote from the fire box 18 is a steam dome 28 traversed by a smoke flue 29 which may be made corrugated, thereby increasing its heat-conducting surface and also strengthening the structure so that braces may be omitted. The flue 29 will therefore constitute a superheat-

ing means for steam within the dome 28. The flue 29 may terminate above the dome 28 in a collar 30 to which may be applied a smoke pipe, or, in some cases, the products of combustion may escape to the atmosphere directly from the collar 30.

Water is introduced into the boiler for a sufficient depth to cover the shell 2, the water being indicated at 31 in Figure 1. When fuel is burning in the fire box 18 the hot products of combustion rise into the shell 2, heating the walls thereof and also heating the water tubes 9, such products of combustion following the tubes 9 until reaching the smoke flue 29 and then rising through the latter to escape to the atmosphere. The hot products of combustion in the fire chamber and circulating about the water tubes 9 and against the inner walls of the shell 2 heat the water between the shells and in the tubes to the steaming point, the steam collecting in the steam dome 29 from which the steam may be taken for useful purposes as is customary. There is provided a very large heating surface so that steaming may occur rapidly. The tendency of the shells to separate under the steam pressure is resisted by the stay bolts 3 and 4 and braces 15^a as well as by the rods 21 or stay bolts 26 as the case may be. The extensive connections between the inner and outer boiler shells and between the heads 13 or between said heads and the plates 8 permit the boiler to resist internal pressure without the necessity of using metal of the thickness heretofore employed.

By making the dome 28 of heavier material no interior bracing is needful. This may be readily done because the dome constitutes but a relatively small part of the boiler and the added weight represents but a small fractional part of the weight of the boiler as a whole. The corrugated flue 29 is, because of the corrugations, resistant to collapsing pressures, and, moreover, compensates for expansion and contraction besides providing a much greater radiating surface for a given length.

The ready accessibility of the stay devices represented by the rods 21 or bolts 26 permits the quick dismantling of those parts of the boiler through which the tubes 9 and other interior parts of the boiler must be reached.

Since the products of combustion move about the tubes 9, deposits of soot occur thereon and it becomes necessary to remove such deposits from time to time. To do this cap or caps 3^b are removed from the hollow stay bolts 3^a and a steam or compressed air pipe is connected in place of a cap 3^b, whereby a strong blast may be directed against the soot covered tubes 9 and the accumulations of soot blown therefrom. Deposits of soot also occur on the inner face of the shell 2 beneath the flue 29. To re-

move such accumulations, clean-out passages 32 are provided in traversing relation to the water space between the two shells. These clean-out openings are closed in any suitable 5 manner when not in use.

The boiler is susceptible of use for large or small installations and may be cheaply built as compared with ordinary boiler installations for the same purpose because the 10 boiler shells may be made of lighter material than heretofore without loss of resistance to internal pressure.

What is claimed is:—

15 In a steam boiler, in combination, a pair of concentric shells, a water firebox adjacent

one end of said shells, a plurality of water tubes connected to the end walls of the inner shell, said shells and water tubes being inclined upwardly from the firebox end, a steam dome connected to and projecting upwardly from the uppermost end of the outer shell, a flue passing through the steam dome and communicating with the inner shell, and means for maintaining said shells in spaced relation.

20 In testimony that I claim the foregoing as my own, I have hereto affixed my signature.

25

GEORGE COOK.
